UNITED STATES PATENT OFFICE

2,483,317

CARBON-TYPE MICROPHONE

Charles Laurent, Paris, France

Application January 7, 1946, Serial No. 639,603
In France January 27, 1944Section 1, Public Law 690, August 8, 1946
Patent expires January 27, 1964

5 Claims. (Cl. 179—122)

The invention has for its object various improvements in a microphone diaphragm case, and more especially for an improvement of its telephonic qualities, mainly the clearness, as also a simplification of its manufacture.

To this effect, the new case according to the invention comprises the various special features as follows:

(a) The granule chamber is disposed in such a way that accidental decentering between the part of this chamber united to the movable electrode and that joined to the stationary electrode shall have no influence upon the settling of the carbon powder in this chamber.

(b) The material utilized for this granule chamber, and particularly for its hollow part, can be given a near perfect polish in order to reduce the friction of the carbon powder between the electrodes, friction being the source of detrimental vibrations. Without being restricted to their specific use, the following materials may be used: cellulose acetate, porcelain, glass, etc.

(c) The rear part of this granular chamber has a shape designed to prevent settling of the graphite powder.

(d) The granular chamber is closed by means of two superposed supple diaphragms made of a light fabric such as for example silk, cotton, rayon, etc., the thin lower diaphragm being rough and the upper one impervious to moisture.

(e) The electrodes have a shape designed particularly to provide a high efficiency and to partially aid the efficiency of the microphone attained by the orientation of the seeker. This shape is characterized by a flat portion comprising a central arc.

(f) The general dimensioning permits of obtaining the desired resistance (50 ohm) without any burning out.

(g) A special part allows the adaptation of the mechanical impedance of the granular chamber and of that of the microphone diaphragm, so that the microphone will be at the same time, both, direct acting (agitation of the granules by the electrode) and indirect acting, (agitation of the granules by means of an agitator that, in fact, is constituted by the part of the diaphragm made of rough silk in the adapter plate).

(h) The part that is required in most microphones to lead in the current to the movable electrode independently of the diaphragm is made with a view to modifying, by its elasticity, the characteristics of the utilized usual type vibrating diaphragm, and, more particularly, its output at the high frequencies by modification of the vi-

brating system formed by the whole of the diaphragm, special spring, the movable electrode and its adjusting nut.

(i) A special, slightly elasical part enables the assembly of the whole to be secured by a single joint or setting, without the necessity of any mechanical means that would be difficult to arrange on the case.

(j) A special assembly allows of attaining at the same time fastening of the diaphragm upon the movable electrode, obturating of the chamber, securing of the cited adapter ring and of the spring in *h*, by means of a single nut thereby reducing the inertia of the whole.

15 15 The following description of a preferred embodiment of the microphone diaphragm case as illustrated in the accompanying drawings is given merely by way of example and without being limitative.

20 20 In the drawings:

Fig. 1 is a sectional view of a microphone diaphragm case constructed in accordance with the present invention.

Fig. 2 is a sectional segmental view of a double diaphragm, and

Fig. 3 is a perspective view of a spring member used in the case.

As shown in the drawings, the case comprises a housing *10* containing the entire unit secured therein by a joint *11* by means of a conical ring *12* and the edge *14* of the protecting grate *13*.

The vibrating diaphragm *15* is firmly held between the edge *14* and a specially-shaped metallic element *20* having a thin, slightly elastic part *21* and a heel portion *22* contacting the extremity of the fixed part of the granule chamber *30* which, itself, is inherent in the housing *10*.

The granule chamber *30* is connected to the housing *10* by being gripped between the stationary electrode *40* and the electrode support *41* by means of an insulating plate *38*. The obturation of the granule chamber *30* is obtained by the diaphragm *31* formed of two superposed layers of silk, the lower layer *31b* being rough and the upper one *31a* impervious to moisture. This diaphragm is gripped between the heel *22* of the element *20* and the upper border *32* of the granule chamber, by means of the circular edge *33a* of the part *33* forming a spring and being used to establish the connection between the front electrode *45* and the housing *10* by means of the metallic element *20*.

The spring *33*, as more clearly shown in Fig. 3, is designed so as to modify by its elasticity the characteristics of the vibratory system formed by

the diaphragm 15, electrode 45, adjusting nut 46, and, in an auxiliary way, the elastic part 21 and the several air chambers. This modification has for its object an improvement of the high frequency transmission.

The inner face 35 of the granule chamber 30, made of a suitable material, is carefully polished so as to prevent all parasitic vibrations. The granule reservoir, formed by the cavity 36 in the granule chamber, is designed to avoid settling. The electrodes 40 and 45 are made of either carbon and brass or a gilded brass. The meridian of these planes presents straight parts 42, 47 and circular parts 43, 48. Because of the two circular parts, the granule chamber presents the shape of a spherical cap 37.

Decentering of the axis of the electrode 45 with respect to the electrode 40 is absorbed by the play of the heel 22 due to the flexibility of the elastic part 21 without causing any parasitic deformation of the granule chamber.

A steel disc 34 allows the coaction between the mechanical impedance of the diaphragm and that of the granule chamber.

This disc supports a circular portion 33' of the part 33 by which it is caused to bear upon the edge 47 of the electrode 45.

Finally, the drawing shows clearly how a single nut 46 maintains the diaphragm 15, spring 33, adapter 34, diaphragm 31 and electrode 45.

What is claimed is:

1. In a microphone diaphragm case, a granule chamber, a stationary electrode in said granule chamber comprising a central concave portion and a surrounding straight portion of substantial width, a vibrating diaphragm, a movable electrode connected to said vibrating diaphragm, said movable electrode comprising a central convex portion and a surrounding straight portion of substantial width, said electrodes partially defining said granule chamber and forming a central spherical cup portion therein and a plane portion surrounding said cup portion, said chamber having an angular portion surrounding said plane portion, a circular spring member carrying said movable electrode, a rim maintaining the edge of said circular member and a flexible element united to said rim.

2. In a microphone diaphragm case as claimed in claim 1, an annular plate interposed between said movable electrode and said circular member for adjusting the mechanical impedance of the said granule chamber with respect to said microphone diaphragm, said circular member having a projection thereon for maintaining contact between said annular plate and said movable electrode.

3. In a microphone diaphragm case as claimed in claim 2, a diaphragm between movable electrode and said annular plate closing said granule chamber, said diaphragm comprising two thin superposed supple diaphragms of light fabric, the lower of said diaphragms being rough and the upper of said diaphragms being impervious to moisture, said diaphragm providing obturation in said granule chamber.

10 4. In a microphone capsule, a casing, a vibrating diaphragm carried by said casing, a movable electrode integral with said diaphragm, a fixed electrode secured within said casing, a granule chamber between said two electrodes, the latter being so shaped as to provide therebetween a concave interval surrounded by a straight interval, a cup-shaped member of insulating material in the casing bottom, said cup-shaped member having an annular recess for the granules surrounding said straight interval.

15 5. In a microphone capsule, a casing, a vibrating diaphragm carried by said casing, a movable electrode integral with said diaphragm, a fixed electrode secured within said casing, a granule chamber between said two electrodes, the latter being so shaped as to provide therebetween a concave interval surrounded by a straight interval, a cup-shaped member of insulating material in the casing bottom, said cup-shaped member having an annular recess with a perfectly polished 20 surface.
